[57] CLAIM

The ornamental design for a trophy ornament, as shown
and described.

DESCRIPTION

FIG. 1 is a front perspective view from above of a
trophy ornament showing my new design;

FIG. 2 is a rear perspective view from below of the
trophy ornament, shown in FIG. 1;

FIG. 3 is a front perspective view from above of a
trophy ornament showing a second embodiment of my
new design; and

FIG. 4 is a rear perspective view from below of the
trophy ornament, shown in FIG. 3.

FIG. 1

FIG. 2
